UNITED STATES PATENT OFFICE.

ORLYSTIS M. POTTER, OF LARNED, KANSAS.

TWO-PIECE GARMENT.

1,288,673.

Specification of Letters Patent. Patented Dec. 24, 1918.

Application filed January 5, 1915. Serial No. 602.

To all whom it may concern:

Be it known that I, ORLYSTIS M. POTTER, a citizen of the United States, residing at Larned, in the county of Pawnee and State 5 of Kansas, have invented certain new and useful Improvements in Two-Piece Garments, of which the following is a specification.

My invention relates to combined upper 10 and nether garments, and while especially intended for use with an outer or dress shirt, yet it is also adapted for combination suits of underwear.

One of the purposes of my invention is to 15 provide a means of connecting the garment portions so that the downward strain or pull of the nether garment will be taken mainly by the shoulder portions of the shirt. Another object is to construct the nether garment 20 so that the upward pull of the supports will take up and prevent sagging in the center of the waist band. A further purpose is to provide a combined garment in which the connections between upper and lower 25 portions mutually hold each other in proper position and are entirely concealed so that there are no unsightly tabs, straps or other supports, thereby particularly adapting the garment for athletic purposes and for use 30 when the coat and vest are not worn.

In the drawings forming a part of the specification, Figures 1 and 4 are perspective views of a combined garment embodying my invention; Fig. 2, is an enlarged detail showing one form of the connecting supports; Fig. 3 is an enlarged detail of the nether garment portion from the rear and partly broken away to show a manner of reinforcing the side seams; and Figs. 5 and 6 are 35 patterns of the nether garment.

The shirt or upper garment portion 1 is 40 illustrated in the form of a coat-type but it is evident that the other common form which opens in the rear may be used. I believe the strain or pull should be transmitted to the parts adjacent the shoulders and I have therefore provided the connecting and supporting members shown in Figs. 1, 2, 3, and 4, in the form of straps 7, separate from the 45 garment, which may be secured only at the top at 8, and unattached throughout the intermediate portion, so that they may swing inward toward the body, free from the adjacent portion of the shirt, and to adapt 50 themselves to the pull of the nether garment portion 3. This supporting member 7 re-

mains entirely concealed so that the garment is not disfigured by any exposed tabs or straps and the outer form of the shirt may conform to the usual shape having the ordinary skirt portion which passes down into the trousers, thus forming a neat appearance at the waist. This garment is, therefore, adapted for athletic and other uses in which no outer coat and vest are worn. Moreover 60 the downward pull of the nether garment or drawers 3, upon the supporting connecting members 7, assists in maintaining the shirt in normal position during the various movements of the body.

The supporting straps 8, may be sewed or otherwise fastened at their upper ends to the inside of the shirt to the under-arm seams and preferably near the top thereof so as to be adjacent the parts which extend 70 over the shoulders, thereby transmitting the pull to the shoulders, which I have found to be preferable. Each strap is provided with a series of aligned button holes 9. The nether garment is provided at each side with a button 5, which may be a detachable stud if desired, and which is adapted to enter any of the series of button-holes to properly connect the upper and lower garment portions.

While the nether portion may be the usual form, I prefer to construct it so that the pull on the supports 7, will cause the top or waist band to tend to straighten, and thereby raise the center, drawing it up against the body. I accomplish this by making each leg part 90 substantially as shown in Figs. 5 and 6, representing the front and rear patterns respectively, *a b* being the outer side, and *c d* the inner leg seam. The dotted lines show the position caused by the pull of the supports.

By referring to Figs. 1, 3 and 4, it will be seen that the top of the nether garment normally slopes downwardly at the center of the top margin or waist band. The area of the top opening is slightly larger than the 100 measurement around the hips of the wearer, so that the garment may be put on without requiring the usual front flap opening. If desired, a fly opening 10 may be provided. While the garment is being drawn over the 105 hips, the top opening is more or less circular, the central part dipping or sagging as shown in whole lines. When, however, the straps 7 are fastened to the buttons 5, the pull at each side not only pulls upwardly 110 but also stretches the waist band outwardly, causing the top opening to become elliptical,

bringing the center in against the body and raising the center of the waist band as indicated by dotted lines in Figs. 4 and 5. This is due to the fact that the pull from the 5 shoulders through the straps 7, has an outward horizontal component as well as the vertical component or main pull and I have constructed the garment to utilize this horizontal component. The garment not only 10 fits the body snugly and comfortably but is more simple in construction than the usual nether garment.

In Fig. 3, I have shown at 12, a reinforcement of the side seams which is sometimes 15 desirable, especially in garments for athletes which are subjected to sudden strains.

I claim:—

1. A two-piece garment having a connecting means for the upper and lower garment 20 members, comprising a supporting member secured to the upper garment or shirt adjacent to the under-arm seam thereof, said supporting member being provided with a series of longitudinally alined button-holes and 25 extending adjacent said seam entirely within said upper garment but free from said

garment throughout the length of said series of button-holes, and a complementary fastening means carried by the lower garment and adapted to register with one of said button-holes when the garments are in wearing position.

2. A two-piece garment, comprising shirt and nether portions, the latter having continuous closed front and rear parts with a 35 waist band lowest at the center at the front and the back and fastening means at each side, a supporting member secured to the inside of the upper garment adjacent the under-arm seam and having a series of longitudinally alined button-holes adapted to co-operate with the fastening means on the nether portion when the parts are in wearing position, said supporting member being 40 free from the shirt throughout the length of 45 said series of button-holes.

In testimony whereof I affix my signature in presence of two witnesses.

ORLYSTIS M. POTTERF.
